(57) **CLAIM**

The ornamental design for a tray, as shown and described.

DESCRIPTION

FIG. 1 is a perspective view of a first embodiment of my new tray, which is shown as being transparent;

FIG. 2 is a front elevational view of the tray of FIG. 1, the rear elevational view being the mirror image thereof;

FIG. 3 is a right side elevational view of the tray of FIG. 1, the left side elevation view being the mirror image thereof, but for the different positions of the disclaimed lugs;

FIG. 4 is a top plan view of the tray of FIG. 1;

FIG. 5 is a bottom plan view of the tray of FIG. 1;

FIG. 6 is a perspective view of a second embodiment of our new tray;

FIG. 7 is a front elevational view of the tray of FIG. 6, the rear elevational view being the mirror image thereof;

FIG. 8 is a right side elevational view of the tray of FIG. 6, the left side elevation view being the mirror image thereof, but for the different positions of the disclaimed lugs;

FIG. 9 is a top plan view of the tray of FIG. 6; and,

FIG. 10 is a bottom plan view of the tray of FIG. 6.

The portions of the tray shown in broken lines form no part of the claimed design.
